Fig. 4.

Fig. 5.

A technical line drawing of a three-lobed gear. The gear has three lobes on the outer edge. Inside the lobes, there are two concentric circles. The innermost circle is labeled 'a'. The region between the inner circle 'a' and the outer circle is labeled 'A'. The outermost circle is labeled 'a''. On the outer edge of the gear, there is a small circle labeled '3' at the bottom right. The drawing is labeled 'Fig. 6.' in the top right corner.

UNITED STATES PATENT OFFICE.

JOHN W. SWAN, OF LIMA, OHIO.

STUFFING-BOX.

SPECIFICATION forming part of Letters Patent No. 787,411, dated April 18, 1905.

Application filed February 2, 1904. Serial No. 191,659.

To all whom it may concern:

Be it known that I, JOHN W. SWAN, a citizen of the United States, residing at Lima, in the county of Allen and State of Ohio, have invented a certain new and useful Improvement in Stuffing-Boxes, of which the following is a full, clear, and exact description, reference being had to the accompanying drawings.

- o The object of this invention is to provide a stuffing-box which shall possess the advantages of being self-packing and self-adjustable, so as not to bite the traveling rod, and easily separable in renewing the packing.
- o The stuffing-box is particularly adapted for oil-wells where it is intended to surround the polish-rod. Such stuffing-boxes are used out of doors and in the hands of men who are frequently careless, and it very often happens that in tightening the gland the same is caused to bite the rod, injuring it and causing destructive wear. In obviating this difficulty I provide springs which are adapted to draw the gland into the box. These springs are placed on opposite sides of the box, and located intermediately thereof, on opposite sides of the box, are the tightening-bolts. This arrangement insures an even pressure of the gland into the box and allows a convenient adjustment of the bolts. No harm is done if one bolt is tightened up considerably more than the other, for the action of the springs is not disturbed thereby. The springs keep the packing continually pressed around the rod with the desired tightness. My stuffing-box also provides for the convenient removal of the bolts or other parts, as desired.

The invention may be best summarized as consisting of the combinations of parts to the above end, as hereinafter shown and described.

In the drawings, Figure 1 is a plan of my improved stuffing-box when used in a vertical position--as, for example, around the polish-rod of an oil-well. Fig. 2 is a side elevation of the stuffing-box. Fig. 3 is a side elevation at right angles to Fig. 2. Fig. 4 is a

vertical central section, being taken on the line 4-4 of Fig. 1. Fig. 5 is a plan of the gland. Fig. 6 is a plan of the box which carries the packing, and Fig. 7 is a plan of the 50 yoke for compressing the springs.

Referring to the parts by letters, A represents the box proper, which has a socket *a* for carrying the packing *B* and has at its upper end a guiding-flange *a'*. The lower end of 55 the box, as shown, is threaded at *a''*, whereby it may be screwed into a coöperating part. The gland is designated *C*. It fits within the socket *A* and has a flange *c*. The polish-rod *D* passes through the box and gland and is 60 packed by the packing *B*, which is compressed by the gland within the box. Loosely surrounding the box is a yoke *E*, and between this yoke and the flange *a'*, on diametrically opposite sides of the box, are the springs 65 *F*. These springs are held in place by lugs *a'*, formed on the under side of the flange *a'*, with lugs *e* formed on the upper side of the yoke *E*. The yoke and the flange *c* are drawn toward each other by bolts *G*, of which 70 two are employed on diametrically opposite sides of the box midway between the springs *F*. These bolts when tightened draw the gland into the box and compress the springs *F*. The expansible spring force of the compressed 75 packing and of the springs *F* are thus in equilibrium. As the packing wears the relatively increased force of the springs force the gland *C* farther into the box. Thus the stuffing-box is self-packing. If one of the nuts *g* 80 should be tightened up more than the other, no harm results, for this simply tips the yoke a little out of its normal position on an axis which passes through the lower points of support of the springs *F*, so that the pressure 85 which these springs give to the two sides of the flange *c* on the gland remains equal. Thus there is no tendency of the gland to bite the rod, and one of the great difficulties of stuffing-boxes is overcome.

To allow the convenient removal and assemblage of the parts, the openings *c'* in the

90

flange c , which the bolts C occupy, are made, as shown, with a large portion c' , through which the head g' of the bolt may be passed, and a small portion c'' , which is adapted to be normally occupied by the shank of the bolt without letting the head pass. The yoke E has open slots e' , which the shanks of the bolts occupy, and the nuts d are adapted to seat in recesses e'' on the under side of the yoke, the recesses being such size as to hold the ends against rotation. The flange a' of the box is slotted at a'' to allow the free passage of the bolts G . By this construction the stuffing-box may be tightened by simply turning the heads g' of the bolts G , and no harm is done if one bolt is turned more tightly than the other. When it is desired to remove the gland to replace the packing, the bolts are simply loosened sufficiently to allow the nuts g to descend out of the recesses e'' , whereupon the bolts may be swung outward, as indicated in dotted lines in Fig. 4. To allow this movement, the slots e' and a'' are open-ended, as stated, and, moreover, the portions c'' of the openings in the flange c of the gland have their outer portions beveled downwardly, as shown at c'' .

The yoke E is made to dip beneath the springs F , as shown in Fig. 2, so that the base of the springs will be substantially on a line with the upper surface of the nuts g , so that the springs will not be given any side strain by the twisting of the yoke. The yoke is strengthened by arching cross-ribs e'' .

35 I claim—

1. In a stuffing-box, the combination of the box, a gland therefor, a yoke loosely surrounding the box, bolts connecting the yoke with the gland, and springs outside of the box located intermediate of the bolts for giving the yoke a tendency to move in the direction to force the gland into the box, substantially as described.

2. In a stuffing-box, in combination, a box, a gland adapted to seat therein and having a flange thereon, a yoke loosely surrounding the box, bolts connecting said yoke and flange, springs on opposite sides of the box placed intermediate of the bolts and tending to press the yoke away from said flange, substantially as described.

3. In a stuffing-box, in combination, a box having a flange, a gland seating within the box and also having a flange, a yoke loosely surrounding the box, bolts connecting the yoke and flange of the gland, and springs located intermediate of the bolts and on the outside of the box and compressed between the flange of the box and said yoke, substantially as described.

4. In a stuffing-box, in combination, a box having a flange, a gland seating in the box and also having a flange, a yoke loosely sur-

rounding the box, bolts on diametrically opposite sides of the box securing the yoke and the flange of the gland, and springs on diametrically opposite sides of the box compressed between the yoke and the flange of the box, substantially as described.

5. In a stuffing-box, the combination of a box, a gland adapted to seat therein and having a flange, a yoke loosely surrounding the box, springs tending to force said yoke away from the flange, and bolts occupying openings in said flange and passing through open-ended slots in the sides of the yoke, substantially as described.

6. In a stuffing-box, in combination, a box, a gland adapted to seat therein and having a flange, a yoke loosely surrounding the box, springs tending to force said yoke away from the flange, bolts occupying openings in said flange and passing through open-ended slots in the sides of the yoke, and nuts on said bolts on the under side of said yoke occupying recesses in the yoke, substantially as described.

7. In a stuffing-box, in combination, a box having a flange, a gland adapted to seat within said box and having also a flange, a yoke loosely surrounding said box, springs on diametrically opposite sides of the box between the yoke and the flange of the box, bolts on diametrically opposite sides of the box midway of the springs occupying openings in the flange of the gland and extending through open-ended slots in the sides of the flange of the box and the sides of the yoke, and nuts beneath the yoke in which said bolts screw, substantially as described.

8. In a stuffing-box, in combination, a box having a flange, a gland adapted to seat within said box, a yoke loosely surrounding said box, springs on diametrically opposite sides of the box between the yoke and the flange of the box, bolts adapted to connect the yoke and gland, and nuts beneath the yoke in which said bolts screw, said yoke being arranged to bring the lower end of the springs substantially in the same plane with the upper face of the nuts, substantially as described.

9. In a stuffing-box, in combination, a box, a gland adapted to seat therein and having a flange, a yoke loosely surrounding the box, means tending to move said yoke away from said flange, bolts and coöperating nuts connecting the yoke to the flange, said bolts occupying contracted openings in the flange and having heads thereabove, said contracted openings having adjacent larger openings through which the heads may pass, substantially as described.

10. In a stuffing-box, in combination, a box, a gland adapted to seat therein and having a flange, a yoke loosely surrounding the box, means tending to move said yoke away from

said flange, bolts and coöoperating nuts connecting the yoke to the flange, said bolts occupying contracted openings in the flange and having heads thereabove, said contracted openings having adjacent larger openings through which the heads may pass and said yoke having open - ended slots in its sides which said bolts occupy and having beneath

said slots recesses which the nuts occupy, substantially as described.

In testimony whereof I hereunto affix my signature in the presence of two witnesses.

JOHN W. SWAN.
